CLAIM

(57) We claim, the ornamental design for a device for producing three-dimensional objects, as shown and described.

DESCRIPTION

FIG. 1 is a front perspective view of a device for producing three-dimensional objects, showing our new design;
FIG. 2 is another front perspective view thereof;
FIG. 3 is a rear perspective view thereof;
FIG. 4 is another rear perspective view thereof;
FIG. 5 is a front perspective view thereof with a monitor in a protracted position; and
FIG. 6 is a front elevation view thereof with the monitor in the protracted position.
